No. 878,965.

PATENTED FEB. 11, 1908.

G. KUHN,

SWING.

APPLICATION FILED OCT. 21, 1907.

UNITED STATES PATENT OFFICE.

GEORGE KUHN, OF MEADVILLE, PENNSYLVANIA.

SWING.

No. 878,965.

Specification of Letters Patent.

Patented Feb. 11, 1908.

Application filed October 21, 1907. Serial No. 398,429.

To all whom it may concern:

Be it known that I, GEORGE KUHN, a citizen of the United States, residing at Meadville, county of Crawford, Pennsylvania, 5 have invented certain new and useful Improvements in Swings, of which the following is a specification, reference being had therein to the accompanying drawings.

This invention relates to swings, and its 10 primary object is, to provide a swing with means whereby the occupant may propel the swing.

A further object of the invention is, to provide a novel construction of swing adapted 15 to be either suspended from a porch ceiling or like support, or by means of standards anchored in the ground, and suitably braced.

The construction of the improvement will be fully described hereinafter in connection 20 with the accompanying drawing, which forms a part of this specification, and its features of novelty will be set forth in the appended claims.

In the drawing: Figure 1 is a side elevation 25 of a swing embodying the invention, Fig. 2 is a front elevation of the same, and Fig. 3 is a fragmentary front elevation of a modification.

Referring to Figs. 1 and 2, the reference 30 numerals 1 and 2 designate parallel posts or standards, adapted to be anchored in the ground, and braced by inclined braces 3.

To the inner side of each of the standards is secured a bracket 4 provided with an inwardly projecting threaded pin 5 serving as 35 the pivotal supports for the adjustable side bars 6 of the swing. These side bars are each formed with a series of openings 7 to receive the pivot pins 5, and are secured by 40 nuts 8 fitting the threaded ends of the pins. By providing a plurality of openings 7 in the side bars, the latter may be adjusted to a long or short position.

Projecting from the front sides of the upper 45 ends of the standards 1 and 2 is a yoke or frame comprising parallel arms 9 connected by an integral cross bar 10, the ends of the arms 9 being supported in sockets 11 secured to the standards 1 and 2.

The swing seat consists of parallel bottom 50 bars 12 pivotally secured at the point 13 to the side bars, and connected by slats 14, and back bars 15 pivotally secured to the bottom bars as at 16, and also connected by slats 55 17. The back bars 15 are loosely connected to the side bars by rods 18 pivotally connect-

ed at their ends to said back bars and side bars.

Pivots secured to each of the side bars 1 and 2 is a lever 19, said lever being connected by rods 20 to parallel foot-rest bars 21, pivotally connected to the lower ends of the side bars. The ends of the rods 20 are pivotally secured to the levers 19 and to the foot-rest bars 21, and said bars 21 are connected 65 by slats 22 and a cross-rod 23.

The reference numerals 24 and 25 designate ropes or cables secured at their upper ends to the cross-bar 10, and passing over pulleys 26 mounted upon the projecting ends 70 of a rod 27 extending through openings in the upper ends of the cross bar 6. The lower ends of the ropes are attached to the levers 19.

The operation of the improved swing will be readily understood. The pressure of the 75 feet of the occupant upon the foot-rest operates the levers 19 causing a tension upon the ropes 24 and 25, thus rendering the swing self-propelling, the pivoted connections of the bottom-bars, foot-bars and foot-rest bars 80 affording the required leverage to permit the occupant of the swing to keep it in motion, and regulate its swinging movement.

In the modification shown in Fig. 3, the standards 1 and 2 are dispensed with, and 85 in lieu thereof I employ depending bars or hangers 28, secured to a porch ceiling 29, or like support. The bars or hangers 28 are preferably provided with braces 30 connected at their upper ends to the outer sides 90 of the bars. The other elements of the structure are similar to those already described, and bear the same reference numerals.

I would have it understood that the invention includes all such modifications and variations in the details of construction, as may be resorted to without departing from the terms and scope of the claims.

Having now described my invention what 100 I claim as new, is:—

1. A swing comprising vertical supports, brackets secured thereto, and provided with pivot pins, side bars mounted upon said pins, a frame or yoke projecting from said supports, a seat secured between said side-bars, levers, pivotally secured to said side-bars on opposite sides of said seat, ropes secured at one end to said frame or yoke and at their opposite ends to said levers, pulleys 105 on said side-bars for said ropes, foot-rest bars pivotally secured to said side bars, and con-

nections between said foot-rest bars and levers.

2. A swing comprising vertical supports, braces for said supports, brackets secured to said supports and provided with threaded pins, side bars mounted on said pins, nuts for securing said side bars upon said pins, a rod connecting the upper ends of said side-bars, pulleys mounted upon the projecting ends of said rod, a seat secured between said side-bars, levers pivotally secured to the side bars, a frame or yoke secured to said supports, ropes secured at one end to said frame or yoke and at the opposite ends to said levers, and passing over said pulleys, foot-rest bars pivotally secured to said side bars, and rods connecting said foot-rest bars and levers.

3. A swing comprising vertical supports, brackets secured thereto and provided with threaded pins, side bars mounted upon said

pins, nuts for securing said side bars in position, a rod connecting the upper ends of said side-bars, pulleys mounted on said rod, a seat secured between the side-bars, and comprising bottom-bars pivotally secured to the side-bars, back-bars pivotally secured to the seat-bars, and foot-rest bars pivotally secured to the side-bars, connections between said back-bars and side-bars, levers pivotally secured to said side bars, connections between said levers and foot-rest bars, a frame secured to said supports, ropes connected at one end to said frame, and at their opposite ends to said levers, and passing over said pulleys.

In testimony whereof I affix my signature in the presence of two witnesses.

GEORGE KUHN.
